UNITED STATES PATENT OFFICE.

JAMES V. HIRLEY, OF CINCINNATI, OHIO.

SUPPORT FOR ELECTRIC WIRES AND LAMPS.

SPECIFICATION forming part of Letters Patent No. 286,437, dated October 9, 1883.

Application filed July 30, 1883. (No model.)

To all whom it may concern:

Be it known that I, JAMES V. HIRLEY, a citizen of the United States, and a resident of Cincinnati, in the county of Hamilton and State of Ohio, have invented certain new and useful Improvements in Supports for Electric Wires and Lamps in Cities, of which the following is a specification.

My improvement relates to a method for supporting electric wires used for telephoning, telegraphing, electric lights, and other similar uses.

The object of my invention is to effectively support different systems of wires over the center of streets in a suitable manner, so that the wires of one system will not interfere with the wires of another system at crossing points.

Another object of my invention is also to provide a better method of supporting a single system of wires over the center of streets, all of which will be fully set forth in the description of the accompanying drawings, in which—

Figure 1 is an elevation of my improved arch and supporting frames. Fig. 2 is a plan view of the same. Fig. 3 is a transverse elevation of Fig. 1. Fig. 4 is a sectional elevation of one of the supporting-posts containing a chamber for holding fire-extinguishing chemicals. Fig. 5 is a sectional elevation, showing the foot of one of the supporting-posts of the arch and spanning the man-hole and elevator of a sewer. Fig. 6 represents the foot of one of the posts combined with the fire-plug. Fig. 7 is a perspective view of my improvement erected at intermediate street-crossings.

Where one system crosses another it is desirable to have the two transverse sets of wires separated a considerable distance from each other. It has also been found of great advantage to erect the wires over the center of the streets instead of in close proximity to the buildings or over the sidewalks. My invention accomplishes both of these results. It is also desirable in the use of arches over the streets to have them constructed in a substantial manner, so that each set of arches will form a firm frame of itself. It is also further desirable to place the posts sustaining the arches on street corners in such relation to the fire-plugs and man-holes to the sewers as to cover and protect them without the occupying

of additional space, all of which results are accomplished by my invention.

A, B represent posts erected upon either side of the street, supporting the arch C which spans and overhangs the street at a sufficient elevation to support telegraph-wires without interference with the street travel. A', B' represent similar posts arranged parallel with the former posts and spanning a street, B".

D represents a sub-arch, which springs from the center of arches C, C' and spans street d which crosses street B". The object of this sub-arch D is to carry a set of wires directly over other electric wires supported on arches C, C', being sufficiently removed or elevated so as not to lie in the immediate field of the wires supported on the lower arch.

D' represents frames rigidly attached to the arches C and D by means of brackets b, the feet of which are bolted to the frames and arches, respectively.

c represents insulating material inserted between the foot of arches C, C' and the supporting-posts A, A', B, B' for insulating the arches C, C' from ground-connection. Arch D is in like manner insulated from metallic connection with the arches C, C'. The preferred form of connecting the arch D to arches C, C' is by means of a T-thimble, f, into which the sections of these arches are respectively jointed by screw-threads or other appropriate means.

E represents a bracket attached to the under side of one of the arches for supporting an electric lamp, E'.

i represents an insulator placed between the feet of brackets b and the frames D'.

It is desirable when an arch is to be erected at the four corners of a street-crossing to have it occupy as little space as possible, and not interfere with other improvements usually placed upon the street corners. For this purpose I make the posts hollow, one of which, in Fig. 6, is shown as inclosing the hydrant F, pierced with one or more holes through which the spouts for attaching the hose project.

F' represents a door opening into the interior of post A' for allowing the hydrant-cap to be turned. Post B', in Fig. 5, is shown as covering the man-hole of a sewer.

H represents a windlass, and H' an endless chain depending into the sewer for elevating the offal.

Post B is provided with a chamber adapted in shape and size to hold chemicals for extinguishing fire, which is operated in the usual manner of fire-extinguishers, *h* representing 5 hose-pipe projecting through the post B for attaching a splice-hose for directing the gas upon the flames in the adjacent building in case of fire.

Post A is represented as a patrol-box, which 10 is fully described in a previous application filed by me in the Patent Office June 25, 1883.

C" represents a mail-box upon post A. *I J K* and *I' J' K'* represent posts and arches erected upon either side of the street intermediate street-crossings, and *L* a sub-arch sprung 15 from the top of arches *K K'* and spanning the street. The object of this form of constructing the arch is to provide a substantial structure which will be effectively self-braced 20 against the strain of the wires and the force of currents of wind to which the arches are subjected. When the arches are constructed in this manner they can be sustained upon broad 25 foot-plates, then anchored to a stone platform on the sidewalks without the necessity of digging holes in which to set the posts.

I claim—

1. An arch for supporting electric wires over street-crossings, composed of posts A and B 30 and A' B' and arches C C' spanning over streets, in combination with the transverse arch D sprung across a street, substantially as herein set forth.

2. A compound arch for supporting electric 35 wires over street-crossings, composed of four

posts, one erected on each street corner and made hollow and of sufficient size to protect fire-plugs, sewers, and other similar improvements, in combination with two primary arches and a secondary arch supported on the primary arches, substantially as described. 40

3. A compound arch for supporting electric wires over streets, composed of a single main arch supported on the two primary arches and spanning a single street, substantially as herein 45 set forth.

4. An arch for supporting electric wires over streets, supported upon two posts and insulated from metallic contact therewith, substantially as herein set forth. 50

5. In a compound arch for supporting electric wires over a street, the combination of four base foot-posts, two primary arches supported thereby, a secondary arch supported on the primary arches, and a frame, D', secured to 55 one or more of the arches and insulated from metallic contact therewith, substantially as described.

6. A compound arch for supporting electric wires over streets, composed of four base foot- 60 posts, two primary arches, and a secondary arch supported on the primary arches and forming a self-bracing structure, substantially as herein set forth.

In testimony whereof I have hereunto set my 65 hand.

JAMES V. HIRLEY.
